UNITED STATES PATENT OFFICE.

CHARLES H. WILLIAMS, JR., OF CHICAGO, ILLINOIS, ASSIGNEE TO CHICAGO RAILWAY EQUIPMENT COMPANY, OF CHICAGO, ILLINOIS, A CORPORATION OF ILLINOIS.

THIRD-POINT SUPPORT FOR BRAKE-BEAMS.

1,126,328.

Specification of Letters Patent. Patented Jan. 26, 1915.

Application filed May 26, 1913. Serial No. 769,911.

To all whom it may concern:

Be it known that I, CHARLES H. WILLIAMS, Jr., a citizen of the United States, residing at city of Chicago, State of Illinois, have invented a certain new and useful Improvement in Third-Point Supports for Brake-Beams, of which the following is a full, clear, and exact description, such as will enable others skilled in the art to which it appertains to make and use the same, reference being had to the accompanying drawings, forming part of this specification, in which—

Figure 1 is a detail view of my improved third point support for brake beams. Fig. 2 is a sectional view on line 2—2 of Fig. 1. Fig. 3 is a sectional view on line 3—3 of Fig. 1. Fig. 4 is a sectional view of modified form of mount for the third point support. Fig. 5 is a modified form of mount for the third point support.

This invention relates to a new and useful improvement in third point supports for brake beams, the object being to arrange said support above the brake beam, so that the beam can be readily hung and unhung.

In Patent No. 997,888 granted to me July 11, 1911, I show an arrangement of third point supports for brake beams in which the spring support or inclined track plate is located under the beam and consequently, it is sometimes difficult to unhang the beam without removing said support or swinging it out of the way.

My present invention contemplates location of the supporting track plate above the beam whereby, if it is desired to unhang the beam, this can readily be done without removing said support or track plate.

In the drawings, 1 indicates the spring plank for a car truck in the form of a channel to which is secured the third point support 2 whose ends are inclined to coöperate with a hanger or carrier 4 slidably mounted thereon, said hanger being connected to the end of a support or brake lever post 5 of the brake. This hanger or carrier 4 may embrace the support 2 as shown in Fig. 3 or it may have its shank portion pass through a slot in said support as shown in Fig. 4. This slot is preferably open at the end of the support so that the hanger or carrier may be readily inserted or removed.

In Fig. 2 I have shown a simple form of mounting the support on the spring plank, 55 the same consisting of a block 6 riveted to the spring plank, the overhanging portion of said block being diverted or inclined immediately above the support so as to co-operate with a removable wedge block 7. 60 This removable wedge block has a lug 8 extending between two lugs projecting upwardly from the overhanging portion of the fixed part of the mount, all of said lugs being provided with alining openings to receive a bolt or rivet 9.

In Fig. 5 I have shown a modified form of mount for the third point support, the same consisting of a fixed element 10 having a lip 11 forming a groove which receives the 70 flange of a removable plate 12. When the plate 12 is arranged in position and swung, it is secured in place by a bolt 13 and in this way forms a rigid mount for the third point support. The advantage of these separable 75 mounts resides in the fact that the third point support, if injured in service, can be readily and quickly replaced without requiring special tools as would have to be used where the third point support was 80 riveted to the spring plank.

What I claim is:

1. In a third point support for brake beams, the combination of an inclined track, a brake beam located under said track, and 85 a carrier on the end of the brake lever post or support of said beam for suspending the same under said track.

2. In a third point support for brake beams, a yielding support having an inclined 90 portion, a brake beam arranged thereunder, and a carrier on the brake beam and movable along said inclined portion.

3. In a third point support for brake beams, the combination of a car truck on 95 which said third point support is directly mounted, and a separable mount for engaging said support and holding it on said part of the car truck, whereby said support may be quickly and readily removed in the event 100 of breakage or damage.

4. The combination with a spring plank of a car truck, of a third point support directly engaging said spring plank and a 105 separable mount for holding said third point support in position on the spring plank, one

member of said separable mount being secured to the spring plank and the other being removable therefrom, whereby said third point support may be detached from said 5 spring plank.

5. In a third point support for brake beams, the combination with a part of a car truck, of a third point support removably mounted thereon, a hanger depending from 10 said support and slidably mounted thereon,

and a brake beam arranged under said support and suspended by said hanger.

In testimony whereof I hereunto affix my signature in the presence of two witnesses, this 14th day of May, 1913.

CHARLES H. WILLIAMS, Jr.
